UNITED STATES PATENT OFFICE.

CALEB V. FLEETWOOD AND EDWARD W. MORTEN, OF VINCENNES, INDIANA.

IMPROVEMENT IN BALING-PRESSES.

Specification forming part of Letters Patent No. 42,046, dated March 22, 1864.

To all whom it may concern:

Be it known that we, CALEB V. FLEETWOOD and EDWARD W. MORTEN, both of Vincennes, Knox county, Indiana, have invented a new and useful Improvement in Baling-Presses; and we do hereby declare the following to be a full, clear, and exact description thereof, reference being had to the accompanying drawings, making part of this specification.

The most distinguishing characteristics of our invention are, first, a mode of converting a vertical into a horizontal press, and vice versa; second, a mode of securing the press against "spreading."

Figure 1 is a perspective view of our press in its vertical form. Fig. 2 is a top view of the horizontal form of our press. Fig. 3 is an end view of our driving-wheels. Fig. 4 represents the followers, stirrup, and combined screw-and-toggle movement detached. Fig. 5 shows our door-fastening detached.

Our press in its vertical form may be described as follows:

A A' are two bed-sills, affording support and attachment to four stanchions, B, firmly connected by means of transoms C, beams D, and stay-bolts E.

F F' G G' are doors which, when closed, form part of the inclosing box or trunk in which the hay is to be tramped and pressed. Of these doors the doors F F' only are used in the vertical arrangement, and that only for the purpose of opening the box to hoop the bale. In the horizontal form the door F is permanently closed, and all three of the front doors, F G G' are thrown open in order to fill the box with hay. The doors G and G' are hinged (*g* and *g'*) to the frame on their top and bottom edges, respectively. Each of the two doors G and G' are provided at their free edges with clamps H and H', having claws *h* and *h'*, of which those on the lower door embrace the stanchions B, and are (for the vertical arrangement) perforated to receive pins, which, entering the stanchions, serve to hold the door G permanently shut. The claws *h* *h'* serve to prevent the sides of the press being spread or bulged out in the act of pressing. The door F is hinged (*f*) at one of its vertical edges, and at the opposite vertical edge is secured by a duplex bolt, I, which enters two eyes, J J', on the door. The upper and lower edges of the door F overlapping the doors G and G' ena-

ables all of the front doors, F G G', to be secured by the one duplex bolt or catch I. The vertical form of our press is provided with an upper frame, K, consisting of four posts inserted in sockets in the tops of the stanchions B, and in line with them. The posts K are merely socketed into the stanchions in order that they may be readily unshipped when the press is to be used horizontally, as in Fig. 2. The office of the frame K is to guide the trumper and support the pulleys L, over which the rope M passes, by which the trumper N is suspended.

O O' are two stirrups, whose lower ends enter a head, P. The stirrups O O' occupy vertical grooves Q in the interior of the frame.

The trumper N has two hooks, R R', projecting from its top, which hooks, when the trumper is to serve as a follower, are engaged over the tops of the stirrups. (See Figs. 2 and 4.)

The lower follower, S, and the head P are hinged to opposite extremities of a compound toggle, T, whose two knees carry rollers V, which rest and work upon the beam D. The knees of the toggle have the form of nuts to receive the right and left screw W W', which carries at one end a pinion, X, which meshes with a driving-wheel, Y, to which is attached the sweep Z, to which the team is hitched. The wheel Y is pivoted (*y*) to the beams D in line with the screw W W', and is capable of being turned on said pivot through ninety degrees without ungearing from the pinion, so as to be available for either the vertical or horizontal arrangement. Fig. 1 shows the wheel Y in position for the vertical mode, and Fig. 2 in position for the horizontal pressing, while Fig. 3 represents the said wheel in the act of transposition from the one form to the other.

The stirrups are so formed as to spring outward or away from each other at their upper parts when disengaged from the hooks R R'. The effect of this provision is to keep the stirrups clear of the trumper N, so as not to interfere with the descent and ascent of the latter. The peculiar form of the shoulders 1 of the stirrups enables their extreme upper parts to closely hug the trumper when the latter is used as the upper follower, and to allow it free play when used as a trumper, and the form also acts to stiffen the shoulders.

The trumper may be operated by an inter-

mittent windlass, 2, of any approved construction.

The sides 5 5' of the box are made yielding, and during the acts of tramping and pressing are pressed inward by means of cams 6, which are relaxed when it is desired to eject the hooped and finished bale.

The operation of the vertical form of our press is as follows: The stirrups O O' being elevated, and the trumper N being disengaged therefrom and connected to the intermittent windlass 2, and the doors being closed, the contents of the box are alternately replenished and beaten in the usual manner until the proper quantity of hay has been accumulated. The trumper N, being now attached to the stirrups O O' by means of the hooks R R', becomes in effect the upper follower, and the screw-and-toggle movement V W W' T being started, the two followers N and S advance to meet each other midway of the box, and so as to bring the compressed hay between the two doors F and F', which doors being then opened by releasing the duplex bolt I and a similar one on the rear side, the bale is hooped in the usual way. The yielding sides 5 5' being now relieved by the turning back of the cams 6, the hooped bale is discharged from the press. In the horizontal arrangement (see Figs. 2 and 4) the additional frame K is unshipped, the press is laid over on its back, and the upper follower, N, is permanently secured to the stirrups O O', and the box having been charged with hay, and the entire suit of front (now upper) doors, F G G', having been closed simultaneously by the one duplex bolt I, the pressing is effected in substantially the same manner as with the vertical arrangement. The stirrups O O', being arranged within the timbers of the press, and as close as possible to the hay itself, act more directly and with less strain than

in forms hitherto employed analogous to ours, but whose rods are outside of the press-frame. The provision for pressing the hay equally on both sides has the advantage of permitting the main body of hay to remain in one place, thus avoiding friction and disturbance of the laminations or successive layers of hay and acting to press the bale equally on one sides, whereas in those presses which press wholly from one side the hay has to travel the entire length of the box with so much friction against the sides thereof toward the conclusion of the pressing action as to practically withstand the compressing force of the follower where most distant therefrom, resulting in an unevenly-pressed bale.

We claim herein as new and of our invention—

1. The arrangement of main frame A B C D E, removable trumper-frame K, and reversible driver Y, the whole constituting a provision for converting a vertical into a horizontal press, and vice versa.
2. The combination of the trumper N and hooks R R' with the stirrups O O', adapted to spring outward, so as to be clear of the trumper in the act of beating, as set forth.
3. The provision of the hooked bars or clamps H H' upon the doors G G', to keep the press from "spreading" during the pressing action, as set forth.

In testimony of which invention we hereunto set our hands.

C. V. FLEETWOOD.
E. W. MORTEN.
